ATTORNEY

UNITED STATES PATENT OFFICE.

WALTER G. STANDING, OF SHARPSBURG, PENNSYLVANIA.

CHILL FOR SASH-WEIGHTS.

No. 901,656.

Specification of Letters Patent.

Patented Oct. 20, 1908.

Application filed June 5, 1908. Serial No. 436,785.

To all whom it may concern:

Be it known that I, WALTER G. STANDING, a citizen of the United States, residing at Sharpsburg, in the county of Allegheny and State of Pennsylvania, have invented certain new and useful Improvements in Chills for Sash-Weights; and I do declare the following to be a full, clear, and exact description of the invention, such as will enable others skilled in the art to which it appertains to make and use the same, reference being had to the accompanying drawings, and to the letters and figures of reference marked thereon, which form a part of this specification.

My invention relates to certain new and useful improvements in chills for casting sash weights and consists of the construction and arrangement of parts shown in the accompanying drawings and described in the following specification.

I am aware that patents have been issued for devices of a similar nature, reference being had more particularly to the patent issued January 1st, 1895 to George Buchanan, No. 531,774, which said invention consists of a two part chill having an eye aperture extending transversely through the same from side to side.

My improved chill is in three parts, and aims to overcome certain defects in the said patent above referred to, more particularly to the means I employ in keeping the two halves of the chill from separating when they are in their seat in the flask, thereby avoiding the possibility of forming a blind eye in the sash weight.

Another improved feature I include in my invention is a locking means whereby the two halves of the chill will be prevented from any longitudinal movement, one against the other, when seated in the flask, thereby overcoming any possibility of the flask bleeding, and destroying the entire cast of metal.

Figure 1 shows a longitudinal section of an ordinary sand flask ready for the pour, and having my improved chill in position therein. Fig. 2 is a similar view after the cast has been made, showing a sash weight formed in the sand. Fig. 3 is a detached view of my chill, and Fig. 4 is a top plan view of the same.

Throughout the different views shown in the drawing the numeral 1 designates an ordinary constructed sand flask which is preferably made large enough to accommodate a plurality of weights at one pouring of the metal. The necessary pattern for the

body portion of the weights, is withdrawn from the sand in the usual well known manner, thereby leaving the cavity 2, which is connected by a gland 3 with the transverse main passage 4, which communicates with all the weight cavities in the series, and likewise with the gate 5. After the pattern has been withdrawn from the sand, my improved chill is inserted any required distance in the end of the cavity 2 from which the pattern was drawn; the distance said chill is inserted determining the length of the weight.

The chill which forms the eye end of the weight, and which I consider a great advantage and improvement over those now in use, consists of two approximately similar halves 6 and 7, which, when brought together, with their outer ends in contact with each other, as shown in Fig. 3, will form the main portion of the chill, of a bifurcated construction, and provided with a concave recess 8 for the purpose of forming a rounded head on the weight. Each of the two halves 6 and 7 has formed thereon an extension part 9 and 10 respectively, the metal at the lower edge of each being hollowed out to form the seat 8 which provides the rounded contour of the eye end of the weight.

As will be seen by referring to Fig. 3 the two aforesaid extension members do not meet or contact with each other, except at the extreme lower edge where they join the main portion of the two halves; a space of predetermined width being thus provided between said two extensions. In each of the said extension portions 9 and 10 is formed an aperture 11, and through these openings is passed a sand core 12, which bridges the intervening space between the two extensions, and forms the third member in the completion of my chill. When assembled with the two main body members, and placed in position in the flask, a chilled eye on the weight is formed.

The inner contacting face of either one of the half portions 6 or 7, is provided with a projecting lug 13 which is designed to register and seat in a correspondingly formed recess 14 formed in the opposite member. This construction affords a locking means for preventing the said two halves of the chill from moving one against the other when seated in the flask, and overcomes the possibility of either half being moved away from its required position, thereby avoiding any "bleeding" when the cast is being poured.

2

By forming my chill in three pieces and providing the sand core 12, around which the metal flows, thereby forming the eye of the weight, I am able to avoid the possibility of the poured metal separating the two halves and running in between the same, thereby forming what is known in the art as a "blind eye", which afterwards requires punching, and thus adds to the labor and cost of production.

10 I claim that my improved chill, as constructed and shown, will positively avoid this defect, which is apparent in the patent to Buchanan, referred to. By providing a sand core, as heretofore described, a positive eye will result in every weight and cast, and when the casting is removed from the mold the sand core can be easily broken, and the two halves of the chill separated from the weight.

15 20 I do not claim any novelty in the flask shown, in which the weights are cast, as this feature may be entirely dispensed with, and other means substituted therefor; such for instance as a bed of sand provided with 25 movable ends, or any other suitable construction.

What I claim as new, and desire to secure by Letters Patent is:

1. A three part sash weight chill consisting 30 of two approximately similar members each being provided with an extension part, the inner faces of which are at some distance from each other when the two halves are in engagement; suitable apertures being formed

through each of said extensions; and a sand 35 core seated in said apertures and bridging the space between the two extension portions.

2. A three part sash weight chill consisting of two approximately similar members each being provided with an extension part, the 40 inner faces of which are at some distance from each other when the two halves are in engagement; suitable apertures being formed through each of said extensions; a sand core seated in said apertures and bridging the 45 space between the two extension portions; and means for locking the said two halves against movement one with the other when in the sand.

3. A three part sash weight chill consisting 50 of two approximately similar members each being provided with an extension part, the inner faces of which are at some distance 55 from each other when the two halves are in engagement; registering concaved surfaces to form the rounded outer portion of the eye; suitable apertures being formed through each of said extensions; a sand core seated in said 60 apertures and bridging the space between the two extension portions; and means for locking the said two halves against movement one with the other when in the sand.

In testimony whereof, I affix my signature, in presence of two witnesses.

WALTER G. STANDING.
